DESIGN FOR A RING

Max Kronstadt, New York, N. Y.

Application June 8, 1939, Serial No. 85,390

Term of patent 7 years

To all whom it may concern:

Be it known that Max Kronstadt, a citizen of the United States and resident of New York city, in the county of New York and State of New York, has invented a new, original, and ornamental Design for a Ring, of which the following is a specification, reference being had to the accompanying drawing, forming part thereof, in which,

Fig. 1 is a side elevational view of a ring embodying my new design and showing the same in closed position;

Fig. 2 is a top plan elevational view thereof; Fig. 3 is a view similar to Fig. 1 but showing the same in open position; and

Fig. 4 is a top plan view thereof.

I claim:

The ornamental design for a ring, substantially as shown.

MAX KRONSTADT.
